Inventor:

George R. Eager
per C. Hannay, Atty.

UNITED STATES PATENT OFFICE.

GEORGE R. EAGER, OF NEWTON, MASSACHUSETTS.

IMPROVEMENT IN OVERALLS.

Specification forming part of Letters Patent No. 179,171, dated June 27, 1876; application filed April 12, 1876.

To all whom it may concern:

Be it known that I, GEORGE R. EAGER, of Newton, in the county of Middlesex and State of Massachusetts, have invented certain new and useful Improvements in Overalls and other pantaloons garments; and I do hereby declare that the following is a full, clear, and exact description thereof, which will enable others skilled in the art to which it appertains to make and use the same, reference being had to the accompanying drawings, and to the letters of reference marked thereon, which form a part of this specification, in which—

Figure 1 represents a side elevation of a pair of overalls, to which my improvement has been applied; and Fig. 2 a cross-section of the same, taken through the waistband. Fig. 3 represents an enlarged and detached view of the clasp, as applied to the cord.

My invention relates to a new and improved mode of adjusting the waistband of garments, so as to enable it to be fitted to persons having different-sized waists, and is equally applicable to overshirts and blouses as to overalls, drawers, pants, and other garments having waistbands which require adjustment.

My improvement consists of the application to a garment, provided with a hollow waistband, and a cord or strap arranged therein for the adjustment of the garment of a spring-clasp, so constructed as to allow the cord or straps to be freely drawn through in one direction in the adjustment of the garment; but which cannot be drawn back in the other direction without first raising the clasp from the cord.

To enable others skilled in the art to make and use my improvement, I will now describe it in detail.

In Fig. 1, A represents the body of a pair of overalls, to which the improvement is applied; and B the waistband.

The construction of the latter is better shown in Fig. 2, the back or rear half being represented as hollow, and into which is inserted a cord, a, the inner end b of which is stitched, sewed, or otherwise secured to the waistband. The other end of cord a is passed out of the hollow waistband through an opening, c, at the other end of the hollow of the waistband, and thence through a spring-clasp, C, hereinafter described.

The drawing shows the hollow of the waistband as being confined to the rear half of the

garment; but it may be longer or shorter, as desired, so long as sufficient length is given to enable the garment to be adjusted to the waists of different-sized persons.

The clasp C consists of a stationary clamp-plate, D, carrying a blank buckle, E, which is rigidly secured thereto, and on the upper end of which is pivoted a spring clamp-plate, F. The free ends of clamp-plates D and F, where a cord, a, is used as the means of adjustment, are rounded, and provided with teeth or prongs e, so arranged as to embrace the cord and prevent its retraction until the free plate F has been raised, or where a strap is used their ends may be straight instead of rounded. To the upper side of plate F is rigidly secured one end of a spring, m, the other end of which passes through between the outer face of the upper end of plate F, and the under side of the upper arm n of the blank buckle E, there being a slot cut in plate F for the purpose. The free end of spring m bears against arm n, and forces the free end of clasp-plate F down upon the cord, and hence causes the latter through its prongs to prevent any back-drag through the clasp. The upper end of clasp F is bifurcated and bent around, so as to embrace arm n, and is thereby pivoted to the latter. Plate D, which forms the frame to which all the other parts are attached, is secured to the waistband of the garment close to the opening c, through which the cord or strap is passed by means of a rivet, g, (shown in Figs. 2 and 3,) and both of which will illustrate the action or operation of the clasp.

By slightly shortening spring-plate F it may be used as a clamp, and the teeth dispensed with entirely, but their use is preferred.

Having thus described my invention, what I claim as new, and desire to secure by Letters Patent, is—

A pair of overalls or other garment, provided with a hollow waistband, and a cord or strap, a, and with a spring-clasp, constructed and arranged to operate substantially as shown and described, and for the purpose set forth.

In testimony that I claim the foregoing as my own, I affix my signature in presence of two witnesses.

GEORGE R. EAGER.
